(57) **CLAIM**

The ornamental design for an all terrain vehicle body, as shown and described.

DESCRIPTION

FIG. 1 is a perspective illustration, from the front and left side, of the all terrain vehicle body according to the present invention;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a perspective illustration from the rear and left side thereof; and,

FIG. 8 is a perspective illustration from the front and left side thereof, with the rear cargo box in an open position. Throughout the various figures of the drawings, certain views are not provided. The omission of a particular view is intended to convey that the element(s) depicted is/are plain and unornamented in that omitted view.

Where included, broken lines showing environment or structure are for illustrative purposes only and form no part of the claimed design.

1 Claim, 8 Drawing Sheets
